Primary Examiner — Richard Kearney*Assistant Examiner* — Liv C Anderson(57) **CLAIM**

The ornamental design for a book clip light, as shown and described.

DESCRIPTION

FIG. 1 is a perspective view of a book clip light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged top plan view thereof;

FIG. 7 is an enlarged bottom plan view thereof;

FIG. 8 is another perspective view thereof, shown in an alternate configuration of use; and,

FIG. 9 is another perspective view thereof, shown in an alternate configuration of use.

The broken lines in the drawings depict portions of the book clip light that form no part of the claimed design.
